Primary Examiner — T. Chase Nelson*Assistant Examiner* — Ania Aman(74) *Attorney, Agent, or Firm* — Andrew F. Young, Esq.; Lackenbach Siegel, LLP(57) **CLAIM**

The ornamental design for the induction housing, as shown and described.

DESCRIPTION

FIG. 1 is a front perspective view of the proposed design.

FIG. 2 is a top plan view of FIG. 1.

FIG. 3 is a left side elevation view of FIG. 1.

FIG. 4 is a front elevation view of FIG. 1.

FIG. 5 is a rear elevation view of FIG. 1; and, FIG. 6 is a right side elevation view of FIG. 1, noting no claimed portion is shown.

Statement: No claim is made to the portions shown in dashed broken lines in the images which demarc disclaimed portions. No claim is made the bolt-openings as seen in dashed lines in FIGS. 1, 2, 3, 4, and 5. No view is provided to the bottom plan view as there is no claim thereto.
